UNITED STATES PATENT OFFICE.

CHARLES A. BERRY, OF STAMFORD, CONNECTICUT, ASSIGNOR TO, THE YALE & TOWNE MANUFACTURING COMPANY, OF STAMFORD, CONNECTICUT.

BOLT MECHANISM FOR DOORS.

1,086,125.

Specification of Letters Patent.

Patented Feb. 3, 1914.

Application filed December 26, 1912, Serial No. 738,623;

To all whom it may concern:

Be it known that I, CHARLES A. BERRY, of Stamford, in the county of Fairfield and State of Connecticut, have invented certain new and useful Improvements in Bolt Mechanism for Doors; and I do hereby declare the following to be a full, clear, and exact description of the invention, such as will enable others skilled in the art to which it appertains to make and use the same.

My invention relates to an improvement in bolt mechanism for doors and particularly for hollow metal doors.

In the use of hollow metal doors, it has been found that when a fire occurs in a room, the heat causes the door to warp away from the jamb sufficient to allow the flame to pass through into the next room, and the object of this improvement is to so secure the door by means of safety bolts, in addition to the usual spring latch, that the door will be held in position and prevented from warping.

With this object in view my invention consists in a series of auxiliary or safety bolts connected with the latch bolt actuating mechanism so as to be retracted thereby, and automatically operated means for holding the auxiliary or safety latch bolts normally retracted.

My invention further consists in the parts and combination of parts and in the details of construction as will be more fully described and pointed out in the claims.

In the accompanying drawings, Figure 1 is a view in longitudinal section of a door stile with my improvements attached thereto. Fig. 2 is a view in transverse section on the line A—A of Fig. 1. Figs. 3 and 4 are views in section showing the trip for holding the secondary bolts in retracted position and for releasing them as the door assumes its closing position. Figs. 5 and 6 are views in elevation and section respectively of the lock mechanism, and Figs. 7 and 8 are similar views of a modification of the lock mechanism.

The door is preferably hollow, and mounted in the stile 1 thereof, are a series of bell crank levers 2. These levers 2 are each pivotally mounted on a bracket 3 secured to the inner face of the outer edge of the stile, and each is pivotally connected at its upper end, as at 4, to an auxiliary bolt 5. In the present instance, I have shown three aux-

iliary bolts, but the number used is unimportant. The lower end of each bell crank lever 2 is pivotally connected to the lifting bar 6, so that when the latter is moved vertically, all the bell crank levers 2 will be turned in a direction to retract the auxiliary bolts 5, and when the bar 6 is released, its weight will shift or operate the entire series of bell cranks in a direction to project the bolts 5. The lifting bar 6 preferably extends from a point just below the top bolt, to a point just below the lower bolt. The bolts 5 pass through holes in the outer edge of the stile, and, when retracted rest flush with or slightly within the outer wall of the stile so as to permit the door to fully close.

7 is the main latch bolt, normally projected by the spring 8, and having a slot in its rear end through which a pin on the vertical arm of the bell crank lever 9 rests, the slot in the shank of the bolt permitting the bolt to be forced inwardly without moving said lever, and without actuating the lifting rod. This lever 9 is pivoted to the stile, and is connected at 10 to the tail piece 11, which latter rests on the roll backs 12 and 12^a of the lock. The free end of the horizontal arm of the bell crank lever 9 rests under the pin 13 carried by bracket 14 secured to the lifting bar 6.

From the foregoing it will be seen that if either roll back be turned by a knob, the tail piece 11 will be lifted, and the latter, by its engagement with bell crank 9 turns the latter in a direction to retract latch 11, and by its engagement with the pin 13 on bracket 14, elevates the lifting bar, which, through its connections with the several bell crank levers 2, retracts the entire series of auxiliary bolts. As soon as the knob is released the weight of the lifting bar 6, together with the pressure of the spring 8 operates to project the latch 7 and the entire series of auxiliary bolts.

One of the main features of my invention is the provision of means for normally holding the auxiliary bolts retracted, so that the latter are never projected except under abnormal conditions. One form of mechanism is shown in Fig. 1, and comprises a latching lever 15 pivoted at 16, and provided at the free end of one of its arms with a shoulder 17 adapted to engage the free end 18 of the uppermost bell crank 2. The other and shorter arm of the lever 15, is provided at

its free end with the side enlargements 19 which latter are engaged by the tripping levers 20. The hub of one of these levers 20 is mounted in the outer face of the door, 5 and the other is mounted in the inner face, and each is provided with a spring 21 which normally tends to force the tripping levers in a direction to move the latching lever 15, out of contact with the upper end 18 of 10 bell crank lever 2, and thus release the lifting bar 6, which, as soon as released, projects all the auxiliary bolts. Secured to the outer end of the hub of each lever 20, is an arm 20^a, to the free end of which a sheet 15 metal link 22 is pivoted, and pivotally mounted on studs 23 secured respectively to the inner and outer faces of the doors are the metal links 24. In assembling the parts the levers 20 are turned to put their springs 20 under tension, after which the links 22 and 24 at each side of the door are secured together by a solder which melts at a low heat. From this it will be seen that under 25 normal condition both tripping levers 20 will be held out of contact with latching lever 15, thus permitting the latter to dog the end 18 of the upper bell crank lever 2 and thus hold the lifting bar elevated and all of the auxiliary bolts retracted. If however, an abnormal heat should develop at 30 either side of the door, the solder connecting the links 22 and 24 on the side subjected to the heat, would melt thus disconnecting the links and leaving the lever 20 thus released, free to turn under the action of its 35 spring 21, and engaging its extension 19 of latching lever 15, throw the latter to a position to release the end 18 of bell crank lever 2 and permit the lifting bar to drop 40 by its own weight and project all the auxiliary bolts.

With the construction thus far described, the lifting bar is held in its elevated position, and the auxiliary bolts held retracted, 45 by the fusible connection between the links. The fusible connection between the links may however, melt while the door is in open position, or it may be necessary in the event a fire should start with the door closed, to 50 get into the room where the fire started for the recovery of something therein, and then close the door to prevent the fire from spreading, and under such conditions it is essential that means be provided for holding 55 the auxiliary bolts retracted while the door is open, and for releasing them automatically upon closing the door, so as to lock the same against warping. Such means are shown in Figs. 1, 3 and 4, and consists of 60 an L-shaped trip lever 29 pivoted to the inner wall of the front edge of the door, with its lower free edge projecting through an opening in one face of the door, in a position to engage the door jamb 30 when the door is 65 closed. This lever 29 normally projects by

gravity, through the side face of the door, and is provided adjacent its lower end with a lug 29^a, adapted to engage the underside of the lifting bar stop 31, and hold the latter, together with the lifting bar to which the stop is secured, elevated. This stop 31 is rigidly secured to the bar 6, and when the latter is lifted by a knob, the stop 31 will be in a plane above the lug 29^a on lever 29, and remains there so long as the latch bolt is held retracted by a knob. As the door is opened, the projecting end of the lever 29 leaves the jamb and is then free to gravitate outwardly, thus carrying the lug 29^a under the stop, so that when the 75 knob is released, the lifting bar descends until the stop 31 rests on the lug 29^a, as shown in Fig. 3, thus holding all the auxiliary bolts retracted. As the door comes to a close, the trip lever will be forced inwardly by contact with the jamb, thus carrying the lug 29^a from under the stop, and freeing the latter, and permitting the lifting bar to drop by its own weight and project the bolts. 80

The main latch 7 is independent of the auxiliary bolts, and is at all times, and under all conditions, under the control of the inside knob, and also of the outside knob, except when it is set or locked by a key 95 from the outside.

The mechanism of the lock is shown in Figs. 5 and 6, 32 being the inside knob and 33 the outside one. The outside knob carries a lock actuated by a key 34, and 100 coupled by the connecting bar 35 to the key hub 36. The roll back 12^a, which is coupled to the outside knob, is provided on its lower edge with a recess 37, in which the lug 38 at the free end of one arm of the bell 105 crank lever 39 may be moved for locking said roll back against movement by the outside knob. Lever 39 is pivoted at its elbow, and the free end of the other arm thereof is made V-shape to receive the finger 40 on 110 the key hub 36. By turning the key 34, the key hub 36 is turned through the connecting bar 35, until the finger 40 engages one horn of the V-shaped end of the lever 39, and shifts the latter in a direction to 115 carry the lug 38 up into the recess 37 in roll back 12^a, thus locking the latter against movement. A rotation of the key 34 in the reverse direction, turns the key hub 36 in a direction to throw lug 38 out of the recess 120 37 thus releasing roll back 12^a. Lever 39 is held in its two positions by the spring 41.

In order to prevent the thin metal of the door from collapsing under the pressure of the through screws which clamp the escutcheon plates 43 to the door, I provide the spacing or reinforcing blocks 44 which support the plates and take all the crushing strains off the screws. 125

When the lock is used on doors that swing 130

outwardly, the latch bolt shown in Figs. 1 and 5, might be operated even though the outside knob be set, by inserting a thin instrument between the door and the jamb and forcing the latch bolt back. When the device is used on such doors, it is necessary to provide means for deadlocking the latch bolt, and I have illustrated one form of deadlocking means in Figs. 8 and 9. In this construction a deadlocking bolt 45 is carried on the main bolt 7, by the pin 47 and is controlled by the spring 48, the bolt 45 being slotted for the passage of the pin 47. As the door closes both the main and secondary bolts will be carried into the door by reason of their contact with the jamb, but as there is no opening in the jamb for the deadlocking bolt, the latter will be held in its retracted position as shown in Fig. 7. The deadlocking lever 50 is pivoted to one side of the main latch bolt 7, and when the door is closed, the inner end of deadlocking lever 50 stands in front of post 51, thus preventing the bolt 7 from being forced inwardly by any pressure applied to the outer end of said bolt. When the lock is operated by its knob, the extension 52 on the tail piece 11 elevates the rear free end of the deadlocking lever 50 to a plane above the post 51, thus leaving the latch bolt 7 free to be retracted. When the door is open and the knob released, the deadlocking bolt 45 will be carried to its projected position by spring 48, and the inclined surface of said bolt 45 coming in contact with the overhanging lip 54 of the deadlocking lever 50, elevates the rear end of the latter to a position above the post 51, thus leaving the main latch bolt 7 free to be retracted by the closing of the door.

I make no claim in this application to a lifting bar connected with a series of bolts whereby the bolts will be simultaneously projected by the downward movement of the lifting bar, and combined with a fusible device for normally holding the lifting bar in an inoperative position; nor to the combination of a series of connected bolts adapted to be projected by gravity; fusible means for holding the bolts retracted under normal conditions and mechanical means for holding bolts retracted when the door is open; nor to the combination of a bolt adapted to be operated by a knob, a series of supplemental bolts connected with the knob mechanism so as to be actuated by the latter, fusible means for normally holding the supplemental bolts retracted and mechanical means for holding the supplemental bolts retracted when the door is open and after they have been released by the fusible device, as the same forms the subject matter of a divisional application No. 775,156 filed June 21, 1913.

It is evident that many slight changes might be resorted to in the relative arrange-

ment of parts shown and described without departing from the spirit and scope of my invention. Hence I would have it understood that I do not wish to confine myself to the exact construction and arrangement of parts shown and described, but

Having fully described my invention what I claim as new and desire to secure by Letters-Patent, is:

1. In bolt mechanism for doors, the combination with a latch bolt and means for actuating same, of a series of connected secondary bolts, means for holding them in inoperative position, means for connecting them with the main latch bolt so that they may be retracted with the latter, the main latch bolt having movement independent of the secondary bolts, so that the main latch bolt may operate to latch the door when the secondary bolts are maintained in inoperative position.

2. In bolt mechanism for doors, the combination with a latch bolt and means for retracting same; of a series of connected secondary bolts, means for projecting the latter simultaneously, means for connecting them with the latch bolt whereby they may be retracted with the latter, means whereby the secondary bolts may be held in inoperative position, and automatic means, operating when the secondary bolts are free to operate, for holding the latter retracted while the door is open and for releasing them as the door assumes its closed position.

3. In bolt mechanism the combination with a secondary bolt, and automatically operating means for holding the latter retracted while the door is open, of a main latch bolt, means for retracting same, and means for connecting the secondary bolt with the operating mechanism of the main latch bolt, so that it will be operated simultaneously with the main latch bolt when the door is closed, the main latch bolt however being free to move independently of the secondary bolt when the latter is held in its retracted positions.

4. In bolt mechanism, the combination with a main latch bolt and means for actuating same, of a secondary bolt, means whereby the latter may be held in inoperative position, and means whereby, when the secondary bolt is released, it will engage the mechanism of the main latch bolt and be operated simultaneously with the latter, the main bolt being free to operate independently of the secondary bolt when the latter is in its inoperative position.

5. In bolt mechanism for doors, the combination with a series of connected bolts adapted to be projected by gravity, and means for holding said bolts in inoperative position, of a main latch bolt, means for actuating same independently of the connected bolts, and means whereby when the connect-

ed bolts are released they will be actuated by the main latch bolt mechanism.

6. In bolt mechanism for doors, the combination with a main latch bolt, and a series of secondary bolts, of a vertically movable bar adapted to be lifted by the latch bolt actuating mechanism, means connecting said bar with the series of auxiliary bolts whereby the latter will be projected by the weight of the connecting bar when the latter is released, and means for holding said bar elevated when the door is open, and for releasing same as the door assumes its closed position, the said main latch bolt adapted to be actuated independently of the auxiliary bolts, when the vertical movable bar is in its elevated position.
7. In bolt mechanism for doors, the combination with a main latch bolt and means for retracting same, of a vertically movable lifting bar, a series of secondary bolts, a bell crank connecting each secondary bolt with the lifting bar, and means connecting the main latch actuating mechanism and the lifting bar whereby the latter, when in its lowered position, will be lifted simultaneously with the retraction of the main bolt, the latter being free to operate independently of the secondary bolts, when the vertically movable bar is in its elevated position.
8. In bolt mechanism for doors, the combination with a main latch bolt, a spring for projecting same, and knob mechanism for

retracting it, of a vertically movable lifting bar adapted to have movement independently of the main latch retracting mechanism and to be lifted by the latter, a series of horizontally sliding secondary bolts, and a bell crank lever connecting each secondary bolt with the lifting bar, whereby all of the secondary bolts will be retracted simultaneously with the main latch.

9. In bolt mechanism for doors, the combination with a lifting bar, a stop thereon, a series of bolts, means connecting the several bolts with the lifting bar whereby the bolts are actuated by the bar, and a spring actuated main latch bolt, of knob mechanism for retracting the main latch bolt and also for lifting the bar to retract the said series of bolts, and a gravity trip lever carried by the door and adapted to engage the door frame when the door is closed, the said trip lever engaging the stop on the lifting bar for holding the latter elevated when the door is open, the main latch bolt being capable of movement independently of the other bolts.

In testimony whereof, I have signed this specification in the presence of two subscribing witnesses.
